UNITED STATES PATENT OFFICE.

BELFORD BARNETT, OF CAMDEN, AND WILLIAM LEE MACFARLAND, OF BROOKLAWN, NEW JERSEY.

COMBINED CIGARETTE AND MATCH BOX.

Application filed July 31, 1923. Serial No. 654,844.

To all whom it may concern:

Be it known that we, BELFORD BARNETT, a citizen of the United States, residing at Camden, in the county of Camden, State of New Jersey, and WILLIAM LEE MACFARLAND, a citizen of the United States, residing at Brooklawn, in the county of Center, State of New Jersey, have invented a new and useful Combined Cigarette and Match Box, of which the following is a specification.

Our invention relates to a novel construction of a combined cigarette holder and match case, wherein an outer case is provided, in which the cigarette container, which also functions as match carrier is slidably mounted, the construction being such that the matches are secured to or carried by the container in such a way that the match heads and the match sticks are self-contained and do not protrude beyond or outside of the wall of the container. Our invention further consists of a novel construction of a blank which is scored in a novel manner, whereby the container can be readily formed up from the bent or folded blank, which further embodies other novel features of construction and advantages all as will be hereinafter fully pointed out.

Our invention further consists of a novel construction of a container blank.

By our novel construction, the matches are readily accessible when the cigarette receptacle is pulled part way out of the casing. By our novel device the retail dealers of cigarettes are not put to the expense of furnishing matches with every purchase of cigarettes, and the customer is provided at the time he makes his purchase of cigarettes with matches which are conveniently accessible, whenever it is desired to light a cigarette.

Our invention is equally applicable to a cigarette or cigar container as is evident, and is inexpensive to manufacture and at the same time simple in construction and operation.

For the purpose of illustrating our invention, we have shown in the accompanying drawings an embodiment thereof which is at present preferred by us, since this embodiment will be found in practice to give satisfactory and reliable results. It is, however, to be understood that the various instrumentalities of which our invention con-

sists can be variously arranged and organized and that our invention is not limited to the precise arrangement and organization of these instrumentalities as herein shown and described.

Figure 1, represents a plan view of a blank for a container embodying our invention.

Figure 2, represents a section on line 2—2, Figure 1.

Figure 3, represents a perspective view of a combined cigarette container and match carrier partly withdrawn from its outer case.

Figure 4, represents on an enlarged scale 70 a sectional view of the upper portion of our invention.

Figure 5, represents a vertical sectional view of the cigarette container and match carrier pushed into their enclosing case. 75

Similar numerals of reference indicate corresponding parts.

Referring to the drawings:

1 designates our novel construction of cigarette container and match carrier, the 80 container 2 being shown in Figure 3 as partly withdrawn from its outer case 3. The container 2 is composed of a blank 4, best seen in Figures 1 and 2, and comprising the body portion having the lower tab 5, which is 85 transversely creased or scored at the points 6 and 7, so as to form the transverse bar 8. Above the score or crease 7 is located the central body portion 9, which has the parallel side scores or creases 10, whereby the 90 longitudinal side tabs 11 are formed. The scores or creases 10 form a continuation of the lower edges 12, and the upper edges 13 of the members 16 and 17, as will be apparent from Figure 1. The upper portion of 95 the blank is transversely scored or creased as indicated at 14 and 15, whereby the transverse bar portion 16 is formed which terminates in a foldable tongue or flap 17. In the body portion 9 is formed the opening 18, 100 through which the match sticks 19 project, so that their heads 20 lie within the walls of the container blank as will be understood from Figures 2, 4, and 5. The lower ends of the match sticks 19 are secured in position 105 by the strip 21, of adhesive tape or the like, as seen in Figures 2 and 5, and in dotted lines in Figure 1. It will be apparent that when the various creased and scored elements, whereby the members 5, 8, 9, 11, 16, 110

and 17 are formed are bent into position as seen in Figure 3 to form the container, the latter can be readily inserted into or withdrawn from its case 3, which is provided with the match scratcher 22. The case 3 can be provided with the asbestos strip 23 on its inner surface best seen in Figure 4, so that the match heads 20 will not be abraded or caused to ignite when the container, containing the 10 cigarettes 24 is withdrawn from or pushed into its case. It will be seen from the foregoing that by fashioning a blank 4 in the manner described, making the opening 18 therein, securing the matches to the blank 15 in the manner described, a very cheap and efficient means is provided for producing the container and when the container and its case are assembled as seen in Figure 3, a combined cigarette container and match carrier 20 is produced, with the cigarettes and matches all neatly assembled in convenient relation, as is evident. It will of course be understood that the cigarettes 24, may be encased in tin foil 25, as seen in Figure 4, and that 25 while we have described our invention as applicable to cigarettes, it may be used in conjunction with a cigar case or a case for tobacco or other products requiring ignition. While we preferably position the match 30 strip, as shown, it will be apparent that openings may be provided as indicated in dotted lines at 26 and 27, Figure 1 and the match strips located therein.

It will be apparent that our novel blank 35 containing the match strips, having their sticks and heads proportioned and positioned as shown in Figure 2, enables the container to be cheaply manufactured, and the match heads to be always properly positioned, so that there will be no liability of their igniting, the container and match carrier being manipulated as a unit, as will be understood from Figure 4.

It will be understood from the foregoing 40 that our novel package or invention is applicable to all containers adapted to contain

tobacco or tobacco products in any form or any other material that requires ignition, and that further any desired packaging material, such as paper, cardboard, tin, wood, 50 metal or any other material may be employed for the container or its case. It will further be understood that the matches may be of any desired length, thickness, or material and any desired quantity thereof may be employed, and any suitable method of fastening may be employed other than that shown. It will also be apparent that the striking material 22 may be placed upon any desired 55 point of the container or outer case other than that shown, and that the aperture or opening for the reception of the matches may be positioned in other places than that shown. Said apertures also may be of any shape desired to accommodate the style of 60 match or to serve as an insert for the finger when sliding the contents out of the case. Our invention may also be embodied in fire 65 resisting materials of any desired description, which may be placed wherever expedient for the safety of the package or its 70 contents.

Having thus described our invention, what we claim as new and desire to secure by Letters Patent, is:

A container for tobacco products formed from a blank comprising a body portion and top and bottom and side tabs, said body having an opening therein, an enclosing case for said container, and fire proofing material arranged upon the inner face of said casing which material registers with said opening, in closed position of said casing, a strip of matches secured in said opening so that the match sticks and heads are confined in the walls of said opening.

BELFORD BARNETT.

WILLIAM LEE MACFARLAND.
